UNITED STATES PATENT OFFICE.

JOHANN SCHROEDER, OF BERLIN, GERMANY, ASSIGNOR TO THE FIRM OF BERLINER STICKMASCHINENFABRIK SCHIRMER, BLAU & CO., OF BERLIN, GERMANY.

EMBROIDERING-MACHINE.

No. 872,152.

Specification of Letters Patent.

Patented Nov. 26, 1907.

Application filed November 26, 1906. Serial No. 345,171.

To all whom it may concern:

Be it known that I, JOHANN SCHROEDER, a subject of the King of Prussia, German Emperor, and resident of 35^a Schwedterstrasse, 5 Berlin, Kingdom of Prussia, German Empire, have invented an Improvement in Embroidering-Machines, of which the following is an exact description.

Embroidering machines operated from a 10 crank handle for producing chain-strokes are provided with a thread-feeding tool, which delivers the thread to a hooked needle or properly speaking brings the thread in the path of the needle-hook. These feeders as 15 hitherto known possessed an open hook swinging to and fro around its axis, thereby bringing the thread in the proper position to engage the needle. Now it happened quite often, that the thread would fall out of these 20 hooks, which meant a stopping of the machine each time in order to replace the thread.

To avoid such delays and make a continuous working of the machine possible is one of 25 the objects of this invention. Another one is to enable the operator to change from one stitch-form to another one without much loss of time and without employing a complicated reversing device. The stitch-forms 30 that principally come in consideration are so called "chain-strokes" and "moss"-stitches. In the former ones each loop after being pulled through the cloth by the needle is linked or chained to the preceding loop, 35 whereas in the latter form the loop after being pulled through is left projecting above the cloth, thus giving the embroidery surface a moss like appearance, hence its name. Whenever a change of work from chain- 40 to moss-stitching took place much time was lost in resetting and reversing the machines equipped with thread-feeders of the older type. This is obviated if a thread-feeder as 45 described herein is used in combination with the improved stitch-plate, which also forms a part of my invention. For I found that if I employ a thread-feeder as described, I can simplify the usual form of stitch-plates by 50 doing away with the slots extending from the outer circles of holes—hereafter called the thread-catch-holes—to the edge of the stitch-plate. These slots were a necessity in the older forms of stitch-plates where they were 55 used in combination with a thread-feeder provided with the hook attachment, for the

thread, after being pulled through the feeder body had to be carried sidewise in order to be conducted into the hook of the feeder. My proposed feeder requires but a simple pulling up of the thread by means of one of 60 those well known thread-hooks which is conducted through one of the catch-holes in the stitch-plate, the latter hole being in line with one of the side-holes of the feeder.

The absence of slots in my stitchplate does 65 not limit me to the size of the stitchplate, consequently I can give it any diameter wanted, which is of quite an advantage in practice inasmuch as the rather large feed-bars used now-a-days for advancing the 70 cloth will always remain within the space occupied by the properly dimensioned stitching plate, thus operating upon a perfect level and even plane and never go beyond this space, as has been the case in former con- 75 struction.

The improved and simplified construction of the thread feeder as well as the stitchplate are especially well adapted for producing 80 moss stitches in embroidery work. 80

In order to make my invention better understood I illustrate same by several figures, of which

Figure 1 represents a partial section and a side-view of the feeder, Fig. 2 a top view of 85 the face of the feeder, Fig. 3 a section through feeder-head on line x—x on Fig. 1, Fig. 4 a side-view and Fig. 5 a top-view of a different form of the feeder head. Fig. 6 is a top view of the new form of the stitching plate and 90 Fig. 7 is a sectional side-view through the center of the stitching plate. Fig. 8 illustrates in a sectional view the position of needle, feed-bar and stitch-plate for making 95 "chain"-stitches, the needle being in an upward motion and the cloth advancing in the direction of the arrow. The section is taken on line y—y of Fig. 9. Fig. 9 shows a top view of the arrangement represented by Fig. 8 in 100 a position just ready to begin making chain-strokes, the feed-bar being shown in dotted lines. The thread t has been pulled through side-hole c of feeder and the latter has been turned 180° in the direction of the arrow shown. Fig. 10 shows a sectional view of 105 the same arrangement as represented by Fig. 8, but for the production of moss stitches section is taken on line z—z of Fig. 11. Fig. 11 represents a top-view of the arrangement shown in Fig. 10 in a position just ready to 110

begin making moss stitches, the feed-bar *e*-
ing shown in dotted lines. The thread has
been pulled through hole *c* of the feeder and
the latter has been turned 180° in the direc-
tion of the arrow shown.

Figs. 1, 2, and 3 represent a feeder *f* con-
structed in form of a plain rotating cylin-
drical body, where the middle part of the
shank is provided with a helix. The surfaces
10 of the head are perfectly smooth, the upper
part of same, the face, shows two small side-
holes *c*, and *c'*, which terminate in the center-
hole *d*. Through one of these small side-
holes the thread is pulled and as will be read-
ily observed a falling out of same is rendered
15 impossible.

If chain-stitches are to be produced the
manipulations are as follows: One of the side
holes, say *c* for instance is placed beneath one
20 of the outer holes *c*² of the stitch plate *p*.
These latter thread-catch-holes are drilled
thus that the center line of each one forms
one straight line with the center-line of the
holes *c* or *c'* of the feeder below. Now a
25 common thread hook is pushed through both
holes *c*² and *c* in order to catch and pull up
the thread coming up through the hollow
center *d* of the feeder. Hereupon the thread
end is caught and held and the feeder is
30 turned 180°, so that the thread is pulled
across the opening *d* of the feeder and there-
by pulled into the path of the needle *n*. This
very condition is illustrated by Fig. 9, where
the feeder *f* is just turned 180° and the thread
35 *t* having been pulled through hole *c* is held at
A. Now the chain stitching commences and
is produced in a form as illustrated by Fig. 8.
The cloth *k* is advanced in the direction of
the arrow *l* by means of the feed-bar *m*. In
40 producing chain-strokes the hooked end *n'*
of the needle *n* must point in the opposite di-
rection of the advancing cloth in order to in-
terlock each thread loop pulled through the
cloth *k* with the preceding one. The needle
45 *n* works and pulls the thread through holes *n*²
on the second inner row of the stitch plate,
called the stitch-holes. If moss stitches are
to be produced, there is no further manipu-
lation necessary but to reverse the direction
50 of the needle hook *n'* by turning it 180° (see
Figs. 10 and 11), so that the needle hook *n'*
points in the direction of the advancing cloth
and hereupon the thread is to be exchanged
from side-hole *c* to side-hole *c'*. Then again
55 the feeder *f* is turned in the direction of the
arrow shown and the thread—this time com-
ing up through hole *c'*—is carried across hole
d of the feeder *f* and thereby in the path of the

needle hook *n'*, the end of the thread *t* being
held at B. Now the sewing of the moss 60
stitches may begin. The needle hook *n'* in
its upward motion catches the thread *t* and
carries it in form of a loop through the cloth,
but as the hook *n'* points in the direction of
the advancing cloth *k*, it follows, that the 65
hook slips out of the loop as the latter ad-
vances in the direction of the arrow *l*. Thus
each loop is left projecting above the cloth as
illustrated by Fig. 10.

As it is the principal feature of the new 70
thread feeder to possess two channel-like
guides for the thread in form of holes in-
closed all around, the conclusion presents
itself that the form of the thread-feeder does
not have to necessarily be a cylindrical body. 75

Figs. 4 and 5 show a feeder where the head
e of same is developed in U-shape. Here the
two small side-holes *c* and *c'* are drilled into
special attached wings *e'* and *e*². This con-
struction does not alter the function of the 80
feeder in any respect, as will be readily seen
if comparing it with first described form of
same. It only represents a somewhat sim-
pler form of construction and it is a matter of
course that similar other forms can be em- 85
ployed.

As long as but one particular kind of
stitches are to be produced by the machine
of course one single side-hole in the feeder
would suffice for the thread to pass through. 90
The same thing holds true if provisions are
made to turn the feeder 180° whenever a
change of work from chain stitching to moss-
stitching takes place.

Having thus fully described the nature of 95
my said invention, what I desire to secure by
Letters Patent of the United States is:

In an embroidering machine, a hooked
needle, a thread feeder adapted to be oscil-
lated through 180° acting to thread the 100
needle and provided with two oppositely
situated holes through one of which the
thread is passed and a stitch plate provided
with two rows of holes, the holes of each row
equidistant from the center of the plate and 105
the holes of one row being located so as to co-
operate with the holes in the thread feeder
and the holes of the other row situated so
that the needle may pass therethrough, sub-
stantially as described.

In witness whereof I have hereunto set my
hand in the presence of two witnesses.

JOHANN SCHROEDER.
